UNITED STATES PATENT OFFICE.

JAMES C. FITZSIMMONS, OF OAKLAND, CALIFORNIA.

OIL-BURNER.

No. 897,611.

Specification of Letters Patent.

Patented Sept. 1, 1908.

Application filed April 3, 1908. Serial No. 424,883.

To all whom it may concern:

Be it known that I, JAMES C. FITZSIMMONS, citizen of the United States, residing at Oakland, in the county of Alameda and State 5 of California, have invented new and useful Improvements in Oil-Burners, of which the following is a specification.

My invention relates to oil-burners, and especially oil-burners employing crude oil or 10 heavy distillate and air as a volatilizing medium, as distinguished from steam.

With burners in which air is used to volatilize the oil, it is essential, or at least highly preferable, for practical results, to bring the 15 oil and air together inside the burner, and to discharge them through the tip thoroughly mixed as one vapor. Long experience with the use of oil as a fuel in furnaces and in connection with boilers, has taught me that best 20 results are obtained where the passages in the burner are as small as possible.

The invention consists of the parts and the construction and combination of parts as hereinafter more fully described and claimed, 25 having reference to the accompanying drawings, in which—

Figure 1 is a longitudinal section of my burner head. Fig. 2 is a plan view of same.

A represents a burner head of special construction adapted to be screwed on over the 30 end of the air pipe 2. 3 is the oil pipe arranged concentric with the air pipe 2 and separated from the air pipe 2; the outer end of the oil pipe being suitably supported in the hollow 35 spacing member 4. This spacing member 4 comprises a ring into which the oil pipe 3 screws, and having the legs 5 engaging the inside of the air pipe, and also having a part 6 around which the oil is deflected laterally 40 and is brought into intimate association with the body of air in the burner.

The air and liberated oil are thoroughly commingled in the mixing chamber 7 in the burner head A. From this mixing chamber 45 7 extend two vapor passages 8 into the forwardly projecting forked nose 9. The nose portion 9 is made substantially half round, and this is split to receive a short piece of tubing 10, preferably open at both ends, and 50 in communication with the passages 8, and having a transverse discharge slot 11 of suitable depth and thickness through which the commingled oil and air is discharged as an inflammable vapor into the furnace. The 55 part 10 preferably consists of a short section

of thin steel tubing, the thinner the better, and fits in a recess formed by the upper and lower portions of the nose 9. A single bolt 12 passes down through the head A, and by means of a nut 13 the tube section 10 is securely 60 clamped in position. The depth of the slot 11 depends on the character of the flame desired. The deeper the slot, the more fan-shaped the flame. The tube 10 can be turned to right or left to send the flame more or 65 less to one side or the other of the axial line of the burner. By having the tube 10 open at both ends, I am able to use a comparatively small diameter of tubing, because the tube is thereby enabled to carry twice as 70 much vapor as it would if the vapor could enter only at one end. By this construction of burner, the oil and air are thoroughly commingled inside the head, and the discharge through the slot 11 is as a single vapor, which is readily ignited.

The oil and air pipes may be connected with any suitable source of supply, and any means, not necessary here to be shown, may be employed to control the flow through 80 them.

By suitably slitting the tube section 10, and properly adjusting the section in the burner to right or left, any sort of a fan-shaped flame, wider or narrower, may be 85 produced, and the flame can be made to fit the furnace.

The use of a single slot through which to discharge all the inflammable vapor, enables this slot to be made larger than where separate steam and oil passages are necessary, and consequently a steadier and better flame can be had, since there is less danger of clogging.

Having thus described my invention, what 95 I claim and desire to secure by Letters Patent is—

1. An oil-burner comprising a forked head having passages in which oil and an atomizing agent are mixed, means for supplying the oil and atomizing agent to said passages, and a short tubular section slotted between its ends and clamped in said forked head and having its ends open to said passages in the head, with means for clamping said section 100 in the head.

2. In an oil burner, a split burner head having a chamber in which oil and an atomizing agent are commingled, means for supplying oil and said agent to said chamber, an 110

22

Independent short tubular section removably held within the split portion of the head, said section having a discharge slot communicating with said chamber, and a clamping bolt extending transversely through the split portion of the burner head for removably securing the section in position.

In testimony whereof I have hereunto set my hand in presence of two subscribing witnesses.

JAMES C. FITZSIMMONS.
